UNITED STATES PATENT OFFICE.

HENRY S. HUNT, OF CATO, NEW YORK.

DESIGN FOR A CREAM-SEPARATOR.

SPECIFICATION forming part of Design No. 29,941, dated January 3, 1899.

Application filed December 9, 1898. Serial No. 698,783. Term of patent 7 years.

To all whom it may concern:

Be it known that I, HENRY S. HUNT, a citizen of the United States, residing at Cato, in the county of Cayuga and State of New York, 5 have invented and produced a new and original Design for Cream-Separators, of which the following is a specification, reference being had to the accompanying drawing, forming part thereof, and which shows a front elevation of the separator complete, the dotted lines respectively indicating the interiorly-concaved centrally open top and the interiorly-concavo-convex bottom.

As shown in the drawing, the leading or 15 material feature of my design consists in a cylindrical body A, having an inward bead 2, a wire-bound lower edge 3, a wire-bound upper edge 4, an interiorly-concaved top or

cover 5, having a central opening, an interiorly-concavo-convex bottom 6, (said cover 20 and bottom being shown by dotted lines,) and a slotted vertical plate 7 upon the exterior of the body. The obverse side of the body is plain, except as to the bead 2 and the beads of the wire-bound upper and lower ends. 25

Having described my invention, what I claim as new, and desire to secure by Letters Patent, is—

The design for a cream-separator, as herein shown and described.

In witness whereof I have hereunto set my hand this 7th day of December, 1898.

HENRY S. HUNT.
